Fig. 6

Fig. 3

Fig. 7

Fig. 8

Fig. 4

FIG. 1 is a side perspective view of a sport shoe adapted to be worn on the right foot showing my new design;

FIG. 2 is an enlarged front view thereof;

FIG. 3 is a top plan view;

FIG. 4 is a rear view;

FIG. 5 is a side perspective view of the left sport shoe with the ornamentation thereon modified as shown;

FIG. 6 is an enlarged front view thereof;

FIG. 7 is a top plan view; and

FIG. 8 is a rear view.

I claim:

The ornamental design for a sport shoe, substantially as shown and described.
